SALTCELLAR

Robert G. Schwarz, New Orleans, La., and
Adolph H. Vorbusch, Pass Christian, Miss.

Application June 24, 1932. Serial No. 619,134

4 Claims. (Cl. 65—57)

The invention relates to salt cellars, and has for its object to provide a device of this character with a slidably mounted member within the cellar, and adapted to reciprocate as the cellar is reciprocated during the shaking operation for breaking up salt which may become solidified within the cellar incident to dampness and the like.

A further object is to provide yieldable means cooperating with the slidable member for taking up the shock of the slidable member, particularly as it reaches its ends of reciprocation.

A further object is to slidably mount the slidable member on an axially disposed shaft within the cellar and terminating in coiled portions for taking up the shock. Also to provide coiled springs around the shaft and interposed between the slidable member and the helical springs at the ends of the shaft.

20 A further object is to provide the slidable member with radial agitating arms for breaking up the cellar contents.

With the above and other objects in view the invention resides in the combination and arrangement of parts as hereinafter set forth, shown in the drawings, described and claimed, it being understood that changes in the precise embodiment of the invention may be made within the scope of what is claimed without departing from the spirit of the invention.

In the drawings:

Figure 1 is a vertical transverse sectional view through the cellar.

Figure 2 is a horizontal sectional view taken on line 2—2 of Figure 1, showing the slidable member in top plan view.

Figure 3 is a vertical transverse sectional view through another form of the invention.

Figure 4 is a horizontal sectional view taken on line 4—4 of Figure 3.

Figure 5 is a vertical transverse sectional view through another form of the device.

Figure 6 is a horizontal sectional view taken on line 6—6 of Figure 5.

45 Figure 7 shows a vertical transverse sectional view through a further form of the device, and similar to Figure 5 with the exception of the use of a helical spring for a tapered cellar.

Figure 8 is a vertical transverse sectional view 50 through a cellar showing a further form of the device.

Figure 9 is a horizontal sectional view taken on line 9—9 of Figure 8.

Referring to the drawings, and particularly to 55 Figures 1 and 2, the numeral 1 designates the

salt cellar, which is provided with a conventional form of removable perforated cap 2.

It has been found that salt and other condiments become solidified within the cellars, particularly in damp weather, and to overcome this objection, and at the same time break up the material during a shaking operation, a slidable and axially movable weight 3 is provided, and which weight is slidably mounted on the axially disposed shaft 4, the ends of which terminate in 65 helical spring members 5, which assist in absorbing the shock during the reciprocation of the weight 3, and also assist in breaking up the material as they flex. Weight 3 is provided with radial arms 6, which extend outwardly into material during the reciprocation of the weight for facilitating the breaking up operation, and it will be seen that the arms 6 will assume different radial positions as the weight 3 is rotatably mounted on the shaft 4. Interposed between 70 the weight 3 and the spring members 5, and around the shaft 4 are coiled springs 7, which are alternately compressed by the weight 3 during the shaking operation, and alternately allowed to expand, and which action will further agitate 75 the material in the receptacle 1, insuring a fine breaking up operation.

Referring to Figures 3 and 4 wherein a modified form is shown, in this form the weight 3 with its radial arms 6 is slidably mounted on an 85 axially disposed shaft 8, having shoulders 9 for limiting the movement of the weight, thereby eliminating the spring action if desired. The ends of the shaft 8 are provided with radial arms 10 for assisting in the breaking up operation. 90

Referring to the modified forms shown in Figures 5 and 6, the agitating device comprises a coiled spring 11, which coiled spring, intermediate its ends, is provided with a loop 12, in one of its convolutions, and which loop is received in a 95 channel 13 of a weight member 14, which is preferably spherical shaped, therefore it will be seen that this device can be cheaply manufactured and sold, and it consists of only two parts. During the shaking operation, the spring ends on opposite sides of the weight 14 will be alternately compressed and expanded and all of the spring convolutions as well as the weight will agitate 100 the material in the salt cellar.

Referring to the modified form shown in Figures 7, 8 and 9, and particularly to Figure 7, the structure is the same as in Figure 5, with the exception that the spring 11a is helically shaped and is particularly adapted for use in a tapered receptacle 15. It will be noted that the lower end 110

of the spring 11a can be contracted by a twisting operation, until it will pass through the restricted neck 16 of the cellar, otherwise the operation of the device is the same as in Figure 5, and the 5 same numerals apply thereto.

Referring to the modifications shown in Figures 8 and 9, the axial shaft 16 terminates in coiled spring ends 17, and the weight 3 is slidably mounted on the shaft 16 and receives a shock 10 absorbing effect when it reaches the ends of the shaft 16, during the shaking operation, incident to the compression of the spring 17. In this form the weight is provided with U-shaped arms 18, extending outwardly from the ring 19 disposed in 15 the weight channel 20. It will be noted that the ring 14 and the U-shaped arms 18 are formed from a single piece of wire bent to form and from spring material.

From the above it will be seen that an agitating 20 device is provided in a salt cellar in the form of a weight reciprocating member, positively guided in its reciprocation and provided with spring means, which not only absorb the shock of the weight means, but also acts as a breaking up instrument 25 and prevents the weight member from damaging the salt cellar.

The invention having been set forth what is claimed as new and useful is:—

1. The combination with a salt cellar receptacle having a chamber therein and a perforated discharge end, of an agitating device in said cellar, said agitating device comprising an axially disposed shaft, a weight member slidably mounted on said shaft, said shaft terminating in spring convolutions and coiled springs surrounding the shaft and interposed between the weight member and the spring convolutions of the ends of the shaft. 80

2. The combination with a salt cellar receptacle having a discharge end, of an agitating device in said cellar, said device comprising an axially disposed shaft, said shaft at its ends terminating in axially disposed spring convolutions, coiled springs surrounding the shaft and a weight member slidably mounted on the shaft and interposed between the coiled springs. 85

3. A device as set forth in claim 2 wherein the spring convolutions at the ends of the shaft are helically shaped and tapering in opposite directions outwardly thereby forming relatively large outer convolutions. 90

4. A device as set forth in claim 2 wherein the weight is provided with a plurality of radially disposed agitator arms. 95
